UNITED STATES PATENT OFFICE.

WILLIAM CRAIG, OF BROOKLYN, NEW YORK.

APPARATUS FOR PRODUCING CIRCULATION IN STEAM-BOILERS.

SPECIFICATION forming part of Letters Patent No. 351,044, dated October 19, 1886.

Application filed July 15, 1886. Serial No. 208,052. (No model.)

To all whom it may concern:

Be it known that I, WILLIAM CRAIG, of the city of Brooklyn, in the county of Kings and State of New York, have invented a new and useful Improvement in Apparatus for Producing the Circulation of Water in Steam-Boilers, of which the following is a specification.

My invention relates to apparatus whereby water may be withdrawn from the bottom of a boiler having an internal furnace and delivered into the upper part of the boiler by the inducing force of an injecting current of feed-water. In a marine boiler having internal furnaces the water in the bottom of the boiler ordinarily remains very much colder than the water in the upper part of the boiler for a long time after the boiler is set in operation, and by the employment of an injecting current of feed-water to draw water from the bottom of the boiler and discharge it into the upper part of the boiler the water in the boiler will soon be brought to a nearly uniform temperature throughout, and the dangers resulting from unequal expansion of the boiler by the varying temperature in the bottom and upper part of the boiler will be avoided.

In carrying out my invention I employ an injector with the nozzle of which the feed-pipe is directly connected, or with which is connected the discharge-pipe leading from an injector which is operated by a steam-jet to produce the flow of feed-water, and the injector having its nozzle connected with the feed supply, as above described, is connected either directly or indirectly by a suction-pipe with the lower part of the boiler and by a delivery-pipe with the upper part of the boiler. The current of feed-water, whether it be supplied from a feed-pump or from a steam-injector, therefore acts to induce a flow of water from the bottom or lower portion of the boiler into the upper portion thereof, and in order to secure the proper operation of the apparatus it is necessary that the current of feed-water should not pass through the suction-pipe into the boiler, as such operation of the apparatus would frustrate the object of my invention.

My invention consists in the combination, with a steam-boiler having an internal fur-

nace, of an injector through the nozzle of which feed-water is supplied, and which is connected by a suction-pipe with the lower portion of the boiler, and by a delivery-pipe with the upper portion of the boiler, and a check-valve in the suction-pipe between the injector and the boiler, and opening outward from the boiler. By this check-valve the feed-water is prevented from flowing through the suction-pipe into the boiler, and hence the inducing force of the injecting current of feed-water is made effective in producing the flow from the bottom of the boiler through the suction-pipe, injector, and delivery-pipe into the upper part of the boiler.

The invention also consists in the combination, with a steam boiler having an internal furnace and a steam-injector for supplying feed-water thereto, of a second injector with the nozzle of which the delivery-pipe from the first injector is connected, and which is itself connected by a suction-pipe with the lower portion of the boiler and by a delivery-pipe with the upper portion of the boiler. With such a combination of parts the first injector, operated by a steam-jet, forces the feed-water through the nozzle of the second injector and causes it to induce a flow of water from the lower portion of the boiler to the upper portion thereof.

In the accompanying drawings, Figure 1 is a rear elevation, and Fig. 2 is a partial longitudinal section, of a boiler having three internal furnaces and having my apparatus applied thereto, such apparatus being shown partly in section in Fig. 1. Fig. 3 is a side elevation of a part of a boiler having my apparatus in a modified form applied thereto; and Figs. 4 and 5 are sectional views upon a larger scale, representing the injectors and appurtenances as illustrated in Figs. 1 and 3, respectively.

Similar letters of reference designate corresponding parts in all the figures.

A designates the boiler proper, and A' three internal furnaces thereof, which are represented by dotted lines in Fig. 1.

Referring now to Figs. 1, 2, and 4, B designates an injector with a nozzle, B', with which the feed-pipe C communicates, and which is indirectly connected by a pipe, D, with the bottom of the boiler, and directly connected

by a pipe, E, with the upper part of the boiler. I have also here represented a steam-injector, F, with which the pipe D directly communi-
 5 cates, and through which it is connected with the feed-water injector B, and this steam in-
 10 jector F may be operated by steam, which may be taken from a donkey-boiler through a pipe, f, or from the main boiler A through a pipe, f', and which is passed into the injector F un-
 15 der control of the valve f'. The supply-pipe D and the delivery-pipe E are continued by prolongations D' E' within the boiler A, as shown in Fig. 2, and such prolongations are perforated throughout their length, so that the
 20 pipe D' will draw water from different parts of the boiler, and the pipe E' will return the water into different parts of the boiler, and will thereby sooner produce a nearly-uniform temperature of the water in the boiler. I have
 25 represented stop-valves d e in the pipes D E, so that communication between such pipes and their prolongations within the boiler may be controlled, and I have also represented a stop-
 30 valve, c, in the feed-pipe C.

25 In Fig. 4 I have represented in sectional view and upon a larger scale the injector and appurtenances which are represented in Fig. 1.

I do not desire to limit my invention to the employment of any particular kind of steam-
 30 injector F, as an injector of any of the well-known forms may be employed, and the injector F, which is shown in sectional view in Fig. 4, simply illustrates one form of injector which may be employed. The injector F is
 35 provided with a steam-nozzle, f⁴, within which is centrally fitted an adjustable regulating-
 spindle, f⁵; and f⁶ designates a combining-tube, which has the usual overflow-opening, f⁷.

In the operation of my apparatus the feed-
 40 water which is introduced through the pipe C and issues from the nozzle B' of the injector B forms an injecting current, which induces the flow of water from the bottom of the boiler through the pipe D' D and delivers such water
 45 into the upper part of the boiler through the pipe E E'.

In order to insure the proper action of the apparatus it is necessary that the feed-water, which is cold, and therefore is of greater specific
 50 gravity than the water in the boiler after the furnaces therein are lighted, should be pre-
 vented from taking a downward course and entering the bottom of the boiler through the pipe D D', as such a course of the feed-water
 55 would entirely frustrate the purpose of the apparatus. To prevent this I provide in the pipe D, and between the connection of such pipe with the boiler and the injector, a check-valve, d', which is represented in section in Fig. 4,
 60 and which may be of any suitable construction, so long as it is arranged to open outward from the boiler and in a direction toward the injector B. This check-valve will effectually prevent the flow of the feed-water from the injector B
 65 downward through the pipe D, but will permit water to flow freely from the pipe D D'

upward to the injector B, and thence upward into the boiler through the pipe E E'. I have also here represented other pipes, D² D³ D⁴, which connect with the pipe D under control
 70 of valves d² d³ d⁴. I have also shown a pipe, E², leading from the feed-water injector B and controlled by a valve, e'. These several pipes D², &c., and E² form no part of my invention, and they provide, when the steam-injector E is used, for drawing water from the sea in case
 75 of fire, or from the bilge in case of leakage, or from a hydrant or fresh-water supply when the vessel is in dock, and for discharging water through the pipe E², either overboard, if the water is taken from the bilge, or into any part of the vessel in case of fire. The steam-injector F may be operated by steam from a donkey-boiler to circulate the water in the main boiler while getting up steam in the
 80 boiler A, and after steam is gotten up the steam-injector may be stopped and feed-water may be introduced through the pipe C and nozzle B', thereby inducing a flow of water through the pipes D E from the bottom
 85 of the boiler.

In the example of my invention shown in Figs. 3 and 5 a different arrangement of the injectors is represented. In these latter figures the steam-injector F has the feed-pipe C connected with it, and steam introduced through the pipe f', induces the flow of feed-water through the check-valve h and the injector-nozzle B' of the second injector, B, upward through the pipe E into the upper part
 90 of the boiler. The second injector, B, is directly connected by a suction-pipe, D, with the bottom of the boiler, and the current of feed-water forced through the nozzle B' by the steam-injector F will induce in the second injector, B, a flow of water from the bottom of the boiler through the pipes D and E into the upper part of the boiler. In this example of the invention also, the suction-pipe D contains a check-valve, d', which prevents the feed-water forced through the nozzle B' by the action
 95 of the steam-injector F from taking a downward course through the pipe D into the bottom of the boiler.

In Fig. 5 I have illustrated in sectional view an injector and appurtenances arranged as represented in Fig. 3. The injector F is or may be like that shown in Fig. 4 for purposes of illustration. In this example of my invention also, an injector of any other suitable construction other than that shown may be employed.

In Fig. 3 the pipes D E are provided with stop and check valves d e.

Where boilers are already provided with a steam-injector for supplying them with feed-water, my invention, as shown in Figs. 3 and 4, may be added at small expense. It is only necessary to disconnect the delivery-pipe of the steam-injector from the boiler and to connect it beyond the usual check-valve, h, with the nozzle B' of the second injector, B, hav-

ing its suction and delivery pipes D E connected with the lower and upper parts of the boiler.

What I claim as my invention, and desire to secure by Letters Patent, is—

1. The combination, with a steam-boiler having an internal furnace, of an injector through the nozzle of which feed - water is supplied, and which is connected by a suction-pipe with the lower portion of the boiler and by a delivery-pipe with the upper portion of the boiler, and a check-valve in the suction-pipe between the injector and the boiler and opening outward from the boiler, substantially as herein described.

2. The combination, with a steam-boiler having an internal furnace, and a steam-injector for supplying feed-water thereto, of a second injector, with the nozzle of which the delivery-pipe from the first injector is connected, and which is itself connected by a suction-pipe with the lower portion of the boiler and by a delivery-pipe with the upper portion of the boiler, substantially as herein described. 20

WILLIAM CRAIG.
